UNITED STATES PATENT OFFICE.

JAMES J. ALLISON, OF ROCKFALLS, ILLINOIS.

BOTTLE-STOPPER.

SPECIFICATION forming part of Letters Patent No. 707,193, dated August 19, 1902.

Application filed November 21, 1901. Serial No. 83,100. (No model.)

To all whom it may concern:

Be it known that I, JAMES J. ALLISON, a citizen of the United States, residing at Rockfalls, in the county of Whiteside and State of Illinois, have invented certain new and useful Improvements in Bottle-Stoppers; and I do declare the following to be a full, clear, and exact description of the invention, such as will enable others skilled in the art to which it applies to make and use the same, reference being had to the accompanying drawings, and to the figures of reference marked thereon, which form a part of this specification.

My invention has reference to stoppers for bottles, and is intended more especially for that class of bottles containing liquids under gaseous pressure from within.

I am aware that stoppers of somewhat similar construction are already known; but they would be of no use in bottles of the class just named, as the pressure from within would force such stoppers from the bottles. Said stoppers also possess some defects which my invention seeks to remedy, as will hereinafter more fully appear.

Heretofore in bottles designed to hold soda-water and similar liquids upon opening such bottles the entire contents thereof were released or had to be emptied therefrom at once, whereas in my invention the contents of the bottle can be drawn therefrom at different times in desired quantities.

In the drawings, Figure 1 represents the top of a bottle provided with my device in elevation. Fig. 2 is a vertical cross-section thereof. Fig. 3 is a detailed view of the stopper-valve and stem in perspective.

1 is the usual bottle designed to contain soda-water, seltzer, or other liquids under pressure of gases within the bottle.

2 is the cork, preferably of rubber, located in the neck 3 of the bottle. The cork 2 has a longitudinal perforation 4, through which passes a small tube 5, upon the lower end of which is secured a valve 6, closing such tube, the lower end of the cork 2 furnishing a seat for such valve. The action of the valve 6 is rendered more positive by means of the annular ridge 7 on the upper face thereof. The contact between such valve and the cork 2 is secured by means of a button 8, secured on the upper part of the tube 5, and an exten-

coiled spring 9, interposed between the button 8 and the top of the bottle. In order to give to such top a more finished appearance, 55 a cap 10 is placed over the same, furnishing a seat for the spring 9, such cap being perforated to permit the passage and free longitudinal movement of the tube 5. The upper end of the tube 5 may be provided on its outer 60 circumference with a thread 11 and the button 8 perforated and threaded to correspond thereto, by which means the force of the spring 9 may be increased or diminished, as desired. 65

In the upper end of the cork 2 is a metallic plug 12 in shape of an inverted cone, such plug being perforated longitudinally to permit of the free movement of the tube 5 therein. The functions of the plug 12 are three-fold—first, it acts as a wedge, forcing the upper part of the cork 2 tightly against the inner face of the neck 3, preventing the removal of such cork; second, it prevents friction between, the tube 5 and cork 2 for almost the entire 75 length of such cork; third, it forms a guide for the tube 5 without producing any friction thereon. To assist in holding the cork in the neck of the bottle, an annular recess 13 may be formed on the inner face of such neck, 80 into which a portion of the cork is forced by the plug 12.

At the lower end of the tube 5 is an aperture 14, normally closed by the cork 2 and permitting a passage of the contents of the 85 bottle through such tube when the tube is forced into the bottle sufficient to bring such aperture beyond the inner end of the cork. After the bottle has been filled the contents thereof can be released as desired by directing the end of the tube 5 into a glass or other receptacle and forcing such tube inward, the 90 contents being forced out through the tube, as in a siphon-bottle. It is apparent that the emptying of the bottle can be checked at any 95 time and the remaining portion of the contents retained therein.

In a construction of stopper heretofore devised having a tube running lengthwise of the cork and the valve at the lower end thereof a bushing has been provided between such tube and the cork for the entire length of the cork. This construction was defective for use in bottles containing liquids under pres-

sure for the reason that if there was any space between the tube and bushing the contents of the bottle upon the valve being opened would be forced through such space, 5 or if the bushing was fitted so snugly upon the tube as to prevent the liquids being forced between such parts then the friction between such tube and bushing would be so great as to render the same inoperative. It will be 10 seen that in my device there is no friction upon the tube 5 except for a short distance at the lower end thereof, the lower end of the cork 2 forming a packing around the tube 5 and at all times preventing a passage of the 15 liquid above the end of such cork except through said tube. The circular ridge 7 upon the valve 6 presses or cuts slightly into the end of the cork 2, rendering the action of the valve more positive, a feature which is of 20 more importance in bottles containing gaseous liquids.

The bottle is capable of being filled or refilled through the tube 5 by reversing the process.

25 What I claim as my invention, and desire to secure by Letters Patent of the United States, is—

1. In a stopper for bottles, the combination, with such bottle, of an elastic cork, 30 adapted to be secured in the neck of the bottle; a tube, extending lengthwise of the cork, providing means of discharge for the contents of the bottle; a valve at the inner end of said

tube adapted to prevent discharge of such contents when said valve is in contact with 35 said cork; means for retaining such valve movably against said cork; and a wedge-shaped plug inserted centrally of the cork, and adapted to force such cork against the inner face of the neck of the bottle, and also 40 prevent friction of such cork upon said tube for the greater part of the length of said cork; substantially as shown and set forth.

2. In a stopper for bottles the combination with such bottles of an elastic cork, 45 adapted to be secured in the neck of the bottle; a tube extending lengthwise of the cork providing means of discharge for the contents of the bottle; a valve at the inner end of said tube adapted to prevent discharge of such 50 contents when said valve is in contact with said cork; means for retaining such valve movably against such cork; a wedge-shaped plug inserted centrally of the cork and adapted to force such cork against the inner 55 face of the neck of the bottle, and also prevent friction of such cork upon said tube for the greater part of the length of said cork; and an annular recess in the inner face of the neck of such bottle substantially as described. 60

In testimony whereof I affix my signature in presence of two witnesses.

JAMES J. ALLISON.
